WATER JUG OR THE LIKE

William Kracht, Jr., 12990 Lincoln Way SW.,
Massillon, Ohio

Filed Nov. 13, 1961, Ser. No. 67,494

Term of patent 14 years

(Cl. D58—5)

FIG. 1

FIG. 2

FIG. 3

FIG. 4

FIG. 5

FIG. 1 is a side elevation of a water jug embodying my new design.

FIG. 2 is a top plan view thereof.

FIG. 3 is a front elevation thereof.

FIG. 4 is a rear elevation thereof.

FIG. 5 is a bottom plan view thereof.

The side opposite that shown in FIG. 1 is identical in appearance.

I claim:

The ornamental design for a water jug or the like, substantially as shown and described.
